UNITED STATES PATENT OFFICE.

VAN B. TAYLOR, OF KINGMAN, INDIANA.

CROSSING-GATE.

1,306,033.

Specification of Letters Patent. Patented June 10, 1919.

Application filed January 3, 1919. Serial No. 269,511.

To all whom it may concern:

Be it known that I, VAN B. TAYLOR, a citizen of the United States, residing at Kingman, in the county of Fountain and State 5 of Indiana, have invented certain new and useful Improvements in Crossing-Gates, of which the following is a specification.

This invention relates to gates, and more especially to those which are mechanically 10 operated and interconnected. The gates serve as automatic signals intended for use at a highway crossing; and the broad object of the invention is to produce a signal system of this kind wherein the gates are 15 automatically set across the highway by the approaching train and are allowed to open by the train and at the time it crosses the highway.

A further object is to attach the system to 20 a railway line having a plurality of tracks.

A further object is to permit the operation of the mechanism by a train moving in either direction.

A further object is to permit the closing 25 of one pair of gates manually when the system is not actuated by a train.

A yet further object is to avoid dislocation 30 of the system by a train which approaches the highway but does not proceed to a point where it will release the gates.

Other objects will appear in the following specification and claims, and reference is made to the drawings wherein—

Figure 1 is a perspective view of a stretch 35 of railway and a highway crossing the same, with my invention applied.

Fig. 2 is a detail of the contact on the cab of a locomotive.

Fig. 3 is an enlarged longitudinal section 40 view through the casing, showing the interior mechanism and the connection of the two shafts.

Fig. 4 is a side elevation, and

Fig. 5 is an edge view partly in section 45 of the trip mechanism.

Fig. 6 is a sectional detail on the line 6—6 of Fig. 3.

Figs. 7 and 8 are details of the mechanism 50 within one pair of the stands which support the gates.

Fig. 9 is a horizontal section on the line 9—9 of Fig. 7.

As shown in Fig. 1, an ordinary highway 55 H crosses a railway R, herein illustrated as made up of four tracks, and at the point of crossing are gates G of any appropriate

type mounted in stands S and capable of being swung down toward each other in pairs to close the highway to traffic while the train is passing. Broadly speaking the 60 purpose of the present invention is to permit an approaching train which is typified in Fig. 2 by the locomotive L to close these gates in advance of itself, and then to open them as it crosses the highway and passes 65 on. The system by which this idea is carried out will now be described.

A main shaft is shown in Fig. 1 as leading from the farther side of the railway R alongside the highway H toward the 70 reader and connecting two stands S, passing meanwhile through a casing 2 whose details are best seen in Fig. 3. Within the stands this shaft is connected to two gates G in a manner yet to be described, and these 75 gates may be connected to companion gates on their respective sides of the railway in a manner also yet to be described. However, it is possible the last named gates might be omitted, and either of the first two gates 80 could be omitted although I have illustrated and described the system as applied to four gates at the point where the highway crosses the railway. The gates themselves may be 85 of an appropriate type, and I have shown them herein as consisting each of a long bar of rather light structure pivoted within the stand and continued beyond the pivot in a short arm carrying a weight W which is sufficiently heavy to cause the gate to stand 90 normally upright. A main spring 3 (see Fig. 9) is attached at one end to the main shaft and at the other end at the point 4 to one of the stands S, and this spring is sufficiently powerful to overcome the weight on 95 the gate or the weights on all the gates, if they are used as herein described, and cause them to swing downward to a horizontal position. Thus it will be seen that it is necessary for the system to include means 100 whereby a passing train permits the spring to act, and when it reaches the highway the train must re-coil the spring and permit the weights on the gates to cause them to resume their upright position. Hereinafter I will 105 call the first action the tripping and the second action the setting mechanism, the latter being within the casing and the former at some distance up the track way. A sleeve 5 surrounds the main shaft and has rigidly 110 mounted thereon a number of fingers 6, one of these standing adjacent one rail of each

track, and Fig. 1 shows that the railway in the present instance is made up of four tracks. What might be called the master finger 7 is forked at its lower end as shown 5 in Fig. 6 and one fork-arm is attached to the sleeve while the other fork arm is attached to a collar 8 on the main shaft 1, the fork itself standing astride the casing 2 through which the main shaft is extended as shown. 10 Thus, any impulse imparted to one of the fingers is communicated to the master finger, and by the latter to the main shaft in a manner yet to be described.

A second shaft 11 parallels the first shaft 15 and its sleeve and extends through the rails as also seen in Fig. 1 and this shaft carries fingers 16 and a master finger 17, the latter also being forked and its fork straddling the casing 2, but the arms of this fork are 20 fast on the shaft 11 direct, as said shaft has no sleeve.

The fork of each master finger has a cross bar 12 passing through curved slots in the walls of the casing, and beneath said cross 25 bar is a spring 13 resting on a shelf 14, the purpose of this detail being to hold the tip of the finger normally a little above its extreme lowest position, so that the contact C on an approaching locomotive L may engage 30 one finger and carry it over toward the center of the casing, and then pass on and over the other finger and depress it slightly, without injury to either. As the two shafts are connected by mechanism next to be described, 35 it is obvious that in whichever direction the contact is moved, it must swing one finger inward and then pass over the other; therefore, only one pair of shafts is necessary and on one side of the highway, 40 and yet provision is made for trains moving in either direction and on any of the several tracks. Restoring springs 18 and 19 respectively connect the forks of the master fingers 7 and 17 with the casing 2, to throw these 45 fingers outward or normally to the positions indicated in Figs. 1 and 3 so that after the train has passed on the cross bar 12 of each fork will rest upon its spring 13.

Mutilated gears 28 and 29 are respectively 50 mounted upon the shafts 1 and 11, each having about one-third of its periphery toothed and the teeth engaging each other. The rear teeth 22 rest normally against the cross bars 12. One gear, as that numbered 29 may 55 have a slot 23 engaging a pin 24 across the casing to positively limit its movement, or in other words to restrict the arc through which it may turn in either direction, and this pin in Fig. 3 is shown at the extremity 60 of the slot so that the gear 29 may not turn farther to the left even though the tip of the fork be yet farther depressed. As this gear is in mesh with the other, its pin-and-slot connection with the casing will hold the 65 other gear against further outward move-

ment. So also the intermeshing of the teeth causes the turning of one gear inward when the other is turned. A tooth or catch 20 projects from the periphery of one gear and is engaged by a latch 21 borne normally toward the smooth edge of this gear by a spring 25 as shown, and chains or wires 26 and 27 lead from the extremities of this latch in both directions for a considerable distance along the railway R and to the trip 75 mechanism yet to be described. When the gears are turned inward far enough for the catch to engage the latch, it is obvious that they will remain in that position until unlatched or tripped, and when so tripped, the 80 uncoiling tendency of the main spring 3 turns the main shaft in a direction to restore the gears to the normal position shown in Fig. 3.

The trip mechanism is best illustrated in 85 detail in Figs. 4 and 5. A shaft 31 extends across the railway and carries a number of duplicate fingers and one finger which may be called the master finger 37 which is mounted on the shaft within a casing 32 and 90 held in normal upright position by a restoring spring 38, as shown in Fig. 5. To the lower end of this finger is attached one of the wires 26 or 27. Its upper portion rises 95 above the casing and is connected to the lower portion by a rule joint 35 and the two portions held normally upright by the spring 38. When now the contact C on a locomotive strikes the upper end of the master finger, or of any of the fingers, if moving to the left in Fig. 4 and the trip finger is turned on its pivot which is the shaft 31 and its lower end gives an impulse to the wire 26 or 27; then the contact C passes along over the setting mechanism described 100 above; and when it reaches the trip finger at the other side of the highway, it passes idly over the upper portion of the corresponding finger because of the presence of the rule joint 35 and spring 34. It follows therefore 105 that a train approaching on any track of the railway will first actuate the trip mechanism and allow the main spring to set the gates G across the highway, then when it reaches the highway the contact C will pick 110 up one of the fingers 6 or 7 and actuate the setting mechanism, or in other words restore the tension of the main spring and permit the weight W on the gate to set the latter again upright, and finally as the train passes 115 the other trip mechanism it does nothing.

I have stated that I do not wish to be limited to the form of gates employed, and that one gate, or two or four may be used. If a pair of gates be employed, the pair in 120 the background of Fig. 1 might well be connected in the same manner as the gates in Figs. 7 and 8. That is to say, on the shaft of the gate is fixed a pulley 40 over which is wound a cord 41 leading downward around 125 130

one groove in a double drum 42 journaled in the stand S. From the other groove in the same drum, another cord 43 leads across and beneath the highway H around a pulley 44 in the opposite switch stand S, and upward and around a pulley 45 fast on the shaft of the companion gate G'. It will now be obvious that when the double drum 42 is turned in the proper direction both cords 41 and 43 will be drawn and the arms of both gates G and G' swung downward against the tendency of the weights W. Buffer springs 46 and 47 may be inserted in the stands to hold the gate-arms horizontal and cushion the impact in case they are closed rather suddenly. When the power which turns the drum in this direction is released, it is obvious that both gates will automatically resume their vertical position as shown in Fig. 1. I need hardly add that the connection between the two gates in the foreground of the last named view may be and probably will be exactly the same, and therefore when four gates are employed instead of two, the action is mere amplification of that set forth.

Occasions occur when it is desirable to close the gate or gates without awaiting the approach of a locomotive bearing the contact C; for instance, it may be a hand car or some other piece of rolling stock which is not equipped with a contact, and it is desirable to have means whereby the gates can be actuated manually. While I do not wish to be limited strictly to the details of this feature, with the construction of parts as already above described, one satisfactory means for providing for manual control is as follows:—At one end (or it might be at each end) of the main shaft 1 where the double drum occurs within the switch stand S, it is connected with the shaft in such manner as to permit a certain lost motion. As herein shown, the drum has a curved slot 52 engaged by a pin 51 in a disk 50 fast on the shaft, the disk preferably moving in a suitable opening within one wall of the stand S. A sleeve 53 encircles the stub end of the shaft and projects through the other wall of the stand S where it carries a handle 54 so that it may be manipulated manually, and on this sleeve the drum is keyed as at 55. With this construction, any impulse imparted to the shaft in the proper direction by the passing train turns the disk 50 and moves its pin 51 in the direction of the arrow in Fig. 7 and sets the gates across the roadway as above described. But if it is desired to set the gate when no train is approaching, then the crank handle 54 is grasped and turned to move the double drum 42 in the same direction, and the result is the same on the gate, although the shaft 1 has not been turned at all. How-

ever, the operator must hold the gate there while the emergency lasts, because it will be remembered it is the turning of the gears which operates the latch mechanism within the casing 2 and holds the gate 70 closed, whereas the closing of the gate by the handle does not actuate the latch mechanism and the gate must be reset by hand instead of by the passing train. I repeat that this specific means for actuating the 75 device manually is not necessarily employed, although I consider it well adapted to the form of gate illustrated and a valuable adjunct to the primary features of the invention. Of course if all gates 80 were connected with the operating drum or drums 42 by cords as described, it would be a simple matter for an operator to merely bear down on the arm of any gate and hold it across the roadway; but the 85 manual mechanism just described would close all four gates by the partial turn of a single crank.

The foregoing description and drawings have reference to what may be considered 90 the preferred, or approved form of my invention. It is to be understood that I may make such changes in construction and arrangement and combination of parts, materials, dimensions, et cetera, as may prove 95 expedient and fall within the scope of the appended claims.

Having thus fully described my invention, what I claim as new and useful and desire to secure by Letters Patent is:— 100

1. In a gate of the type described, the combination with a stand, the gate proper having a long arm and a shorter arm weighted to hold the longer arm normally upright, a pivot through the stand, and a 105 buffer spring carried by the stand to limit the descent of the longer arm; of a pulley fast on said pivot, and mechanism mounted at a lower point within the stand and connected with said pulley for closing the gate 110 and raising its weighted arm and the reverse.

2. In a gate of the type described, the combination with a stand, the gate proper having a long arm and a short arm weighted to hold the longer arm normally upright, and a pivot through the stand; of a pulley fast on the pivot of the gate, a second pulley mounted in the stand at a lower point, a shaft connected with said pulley, a 120 main spring coiled on and connected with the shaft at one end and with the stand at the other end and sufficiently strong to overcome the weight and close the gates, and means for turning said shaft to store 125 energy in the spring and for releasing it mechanically.

3. In a gate of the type described, the combination with a stand, the gate proper having a long arm and a short arm weight- 130

ed to hold the longer arm normally upright, and a pivot through the stand; of a pulley fast on said pivot, a second pulley at a lower point within the stand, this 5 pulley having a slot around its center, a hand lever fast to this pulley for actuating it manually, connections between the two pulleys, a shaft coaxial with the pulley and having a pin projecting into its 10 slot, and means for turning said shaft mechanically.

4. In a railway gate system for highway crossings, the combination with gates at opposite sides of the railway and on one side 15 of the highway, a shaft connecting them, a companion shaft alongside the first-named shaft, gears connecting the shafts, fingers mounted loosely on said shafts and projecting obliquely alongside a rail in opposite 20 directions, for setting the gates to open position, latch mechanism for holding the gears in this position, and trip mechanism at a distant point alongside a rail adapted to be engaged by a contact on an approaching 25 train for permitting the gates to assume a closed position.

5. In a railway gate system for highway crossings, the combination with pivoted gates at opposite sides of the railway, 30 weights throwing them normally open, a shaft connecting them, a companion shaft alongside the first-named shaft, gears connecting the shafts, and fingers mounted loosely on said shafts and projecting 35 obliquely alongside a rail in opposite directions; of a main spring attached to one of said shafts and put under tension when any finger is moved inward and the gates allowed to open, latch mechanism holding 40 said spring under tension, and trip mechanism at remote points alongside the rail and adapted to be struck by a contact on an approaching locomotive for releasing said latch and permitting the main spring to 45 act.

6. In a gate actuating mechanism, the combination with a normally open gate, a shaft connected therewith, a main spring normally turning the shaft to close the gate, 50 a companion shaft, gears on the shafts intermeshing with each other, latch mechanism engaging one of said gears, and trip mechanism for the latch mechanism at a remote point; of fingers carried by said shafts and

projecting normally obliquely in opposite 55 directions, master fingers connected with said other fingers and having forks passing respectively over said gears, springs throwing the master fingers normally outward, 60 springs supporting them in their normal position, and cross bars in their forks engaging certain teeth of said gears, for the purpose set forth.

7. In a gate actuating mechanism, the combination with a normally open gate, a 65 shaft connected therewith, a main spring normally turning the shaft to close the gate, a companion shaft geared to the first shaft, latch mechanism engaging one of the gears 70 for holding the main spring under tension, and remote trip mechanism for said latch mechanism; of a sleeve loose on the first shaft and carrying a number of fingers, a master finger fast on this sleeve and having a cross bar engaging one of said gears, a 75 second set of fingers on the second shaft, the gearing being such that the main spring throws the fingers normally away from each other on oblique lines, and means for supporting them within the path of a contact 80 on a locomotive.

8. In a mechanism of the type described, the combination with a casing adapted to stand alongside a rail, a pair of shafts journaled in said casing, gates connected with 85 the extremities of the main shaft, means throwing said gates normally open, and a main spring coiled on the shaft and of sufficient strength to overcome said means and close the gates; of a pair of mutilated gears 90 fast on said shafts within the casing, fingers having forked inner ends passing astride the casing and loosely mounted on said shafts, cross bars within said forks passing through curved slots in the casing and 95 standing behind the rearmost teeth on the gears, springs throwing the fingers normally apart, a catch on the periphery of one gear, a latch adapted to engage the same, and distant trip mechanism for operating 100 said latch.

In testimony whereof I affix my signature in presence of two witnesses.

VAN B. TAYLOR.
